DESIGN FOR LACE

Bert Edson, Pawtucket, R. I., assignor to New England Lace Mills, Inc., New York, N. Y.

Application July 3, 1934, Serial No. 52,443

Term of patent 3½ years

To all whom it may concern:

Be it known that I, BERT EDSON, a citizen of the United States, residing at Pawtucket, in the county of Providence and State of Rhode Island, have invented a new, original, and ornamental Design for Lace, of which the following is a specification, reference being had to the accompanying drawing forming part thereof in which the figure is a face view of a piece of lace showing my new design.

I claim:

The ornamental design for lace substantially as shown.

BERT EDSON.
